Primary Examiner — Amanda Christensen(74) *Attorney, Agent, or Firm* — KIRTON McCONKIE;
Evan R. Witt(57) **CLAIM**

The ornamental design for a heat sink module as shown and described.

DESCRIPTION

FIG. 1 is a perspective view of a heat sink module showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The break lines that separate parts of the heat sink module represent indeterminate length and form no part of the claimed design.

1 Claim, 7 Drawing Sheets(56)
